UNITED STATES PATENT OFFICE.

MICHAEL J. FITZGERALD, OF RICHMOND, CALIFORNIA.

SASH-WEIGHT.

1,085,081.

Specification of Letters Patent.

Patented Jan. 20, 1914.

Application filed March 25, 1913. Serial No. 756,662.

To all whom it may concern:

Be it known that I, MICHAEL J. FITZGERALD, a citizen of the United States, residing at Richmond, in the county of Contra Costa and State of California, have invented new and useful Improvements in Sash-Weights, of which the following is a specification.

This invention relates to a sash weight, 10 such as is employed for balancing window sashes.

It is the object of this invention to provide a sash weight which is particularly adapted for use in double hung windows.

15 A further object is to provide a sash weight which may be so attached to the sash cord as to relieve the latter of sudden strains on the starting and stopping of the window sash, thus rendering the sash cord less liable 20 to break.

Further objects will appear hereinafter.

The invention primarily resides in detachably mounting a roller having spring bearings on the upper end of a weight, and 25 attaching the weight to the sash cord, and roving the latter under and around the roller, with one of its ends attached to a rigid support and the other connected to the sash in the usual manner.

30 The invention consists of the parts and the construction and combination of parts as hereinafter more fully described and claimed, having reference to the accompanying drawings, in which—

35 Figure 1 is a side elevation of a sash weight constructed in accordance with this invention. Fig. 2 is a detail vertical section on the line *a—a* of Fig. 1. Fig. 3 is a detail side elevation of the roller employed 40 in this invention. Fig. 4 is a detail section and elevation of a double hung window of the mullion type, showing the manner of applying the invention.

In the drawings A represents the body of 45 the sash weight, which may be of any suitable construction, but is here shown as consisting of a cylindrical metallic structure which terminates at its upper end in spaced lugs 2. Formed in the lugs 2 are upwardly 50 inclined slots 3 which are open at their lower ends and terminate at their upper ends on the vertical diameter of the weight body A a short distance below the upper ends of the lugs 2. The slots 3 in the lugs 55 2 are opposite each other, and are designed to receive the ends of a shaft 4, which is

provided with collars 5 on its outer end engageable with the sides of the lugs 2 to hold the shaft 4 against longitudinal movement. Mounted on the shaft 4 is a wheel 6, 60 provided with a circumferential groove 7, adapted to receive a sash rope 8, as will be later described.

The wheel 6 is preferably formed of a pair of sheet metal disks, stamped to shape, 65 which are joined together by rivets 9, or in any other suitable manner. The plates forming the wheel 6 are bent outwardly at their centers to form recesses adapted to receive rollers 10, arranged to bear upon the 70 periphery of the shaft 4. The rollers 10 are provided with trunnions 11 on their ends, which extend through radial slots 12 formed in the wheel 6 and mounted on opposite 75 sides of the wheel 6 are plate springs 13, which bear against the trunnions 11 in such manner as to retain the rollers 10 in contact with the shaft 4, and to provide a resilient bearing for the rollers 10 and the wheel 6.

In the present instance I have shown a 80 series of four rollers 10 as mounted in the wheel 6; it being manifest, however, that this number may be increased to any desired extent. It is also obvious that while I have shown plate springs as being employed and 85 providing for resilient bearing for the rollers 10, any other form of construction may be employed by which a yieldable bearing will be obtained.

90 In the application and operation of the invention the sash weight is connected to the sash cord 8, as shown in Fig. 4; that is the cord 8 is passed around the wheel 6 from the underside, and has one end secured to the sides of a window casing B at C on the 95 interior of the usual channel or box constructed on each side of the sash D, provided for the reception of weights; the other end of the cord being secured to the sash D in the usual manner after passing over direction rollers or sash pulleys E adjacent the upper end of the window frame. From this it will be seen that the weight A is suspended 100 on the cord 8 intermediate the pulley E and the secured end of the cord 8 in such manner 105 that the weight will travel on the cord 8 as the cord moves up or down in relation to the pulley E, when the sash D is raised or lowered in the usual manner.

110 By the provision of the spring bearings for the wheels 6, strains on the sash cords 8, due to the weights A, are cushioned. The

rollers 10 provide non-friction bearings for the wheels 6 and insure a free travel of the wheels 6 on the pulley cords 8, and by providing the slots 3 for the reception of the ends of the shaft, the assembling of the weight A and the wheel 6, and their attachment to the sash cord 8, is greatly facilitated. This construction permits of the weight being attached to the sash cord when both ends 10 of the latter are secured, not necessitating their release, as the wheel 6 may be placed over the sash cord 8 and the weight A connected to the wheel by hooking the slot 13 over the outer ends of the shaft 4; the weight 15 A being retained in position on the shaft 4 by reason of its weight. The angular position of the slot 3 insures the shaft 4 being held against displacement therein.

By the provision of the slideable relation 20 of the weight to the cord, it is possible to replace an old worn cord by a new without taking the weight out of its pocket, this being done by attaching the new cord to the end of the old cord after the latter has been 25 detached at one end, then drawing the cord through the weight, the new cord being attached at its ends as before described.

Having thus described my invention, what 30 I claim and desire to secure by Letters Patent is:

1. A sash weight, comprising a weighted body portion, spaced lugs on the upper end of said body portion formed with parallel inclined slots, a shaft removably mounted 35 in said slots, and a wheel carried on said shaft.

2. In a sash weight, the combination with a weighted body portion of a shaft remov-

ably mounted on the upper end of said body portion, a wheel having a hollow hub portion and formed with radial slots, a series of rollers disposed within the hub of the wheel, trunnions on said rollers extending through the radial slots, and spring members mounted on said wheel bearing against 45 said trunnions.

3. In a sash weight, a weighted body portion, parallel spaced lugs on one end thereof, having inclined slots open at one end formed therein, a shaft adapted to be detachably engaged with said lugs by said slots, collars on the ends of said shaft to prevent longitudinal displacement thereof, a wheel revolvably mounted on said shaft, and resilient bearings between said wheel and shaft. 55

4. In a sash weight, a weighted body portion, parallel spaced lugs on one end thereof, having inclined slots upon one end formed therein, a shaft adapted to be detachably engaged with said lugs by said slots, collars on the ends of said shaft to prevent longitudinal displacement thereof, a wheel revolvably mounted on said shaft, resilient bearings between said wheel and shaft, comprising a series of rollers adapted to travel 60 on the shaft, trunnions on said rollers extending through radial slots in the hub of the wheel, and springs carried by the wheel bearing against said trunnions. 65

In testimony whereof I have hereunto set 70 my hand in the presence of two subscribing witnesses.

MICHAEL J. FITZGERALD.
